(57) **CLAIM**

The ornamental design for a pump housing, as shown and described.

DESCRIPTION

FIG. 1 is a top plan view of the pump housing design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a bottom view thereof; and,

FIG. 7 is a perspective view taken from the top, front and left side thereof.

The broken lines in FIGS. 1 through 7 are included for the purpose of illustrating components of the pump housing that form no part of the claimed design.
